UNITED STATES PATENT OFFICE.

WILLIAM HANKIN, SR., OF BROOKLYN, NEW YORK.

BUCKSAW-BRACE.

SPECIFICATION forming part of Letters Patent No. 380,567, dated April 3, 1883.

Application filed November 15, 1887. Serial No. 255,212. (No model.)

To all whom it may concern:

Be it known that I, WILLIAM HANKIN, Sr., a citizen of the United States, residing at Brooklyn, in the county of Kings and State of New York, have invented certain new and useful Improvements in Bucksaw-Braces; and I do declare the following to be a full, clear, and exact description of the invention, such as will enable others skilled in the art to which it appertains to make and use the same.

My invention relates to bucksaws and braces therefor; and it consists in the novel construction of the parts hereinafter specified and claimed.

This invention is designed as an improvement upon the device shown and described in Letters Patent granted to me June 28, 1870, and numbered 104,847.

In the accompanying drawings, Figure 1 is a side view of a saw constructed according to my improvements. Fig. 2 is a side view of one of the forked braces, and Fig. 3 is a plan view of the same; and Fig. 4 is a view of a modification.

In Fig. 1 of the drawings I have shown the frame of a bucksaw, of which the letter A is the handle, and B the end bar, and C the saw proper, all constructed and united in the usual manner.

The letter D represents a longitudinal brace, bent to form a crescent in shape, and having its ends secured in the handle and bar B, precisely as shown.

E represents metallic rods, affixed to the handle and end bar in the ordinary manner, and provided with a turn-buckle, F, for tightening purposes.

G represents a preferably bifurcated brace connected with the handle A and brace D, respectively, as shown, and is arranged diagonally therewith. A similar brace G, arranged

on the opposite side of the frame, is united to the arm B and brace D in the same manner. My object in bifurcating these diagonal braces is to provide against large mortises and consequent weakening of the several parts. It is obvious, also, that by this method of construction the apparatus is decreased in weight from what it would be were the braces made of a single solid piece of timber. The upper arm of this bifurcated brace is passed into a recess, a, formed in the handle or arm B, while the lower arm thereof rests against the inner side of said handle or brace. A like connection is made with the braces G and D, as fully represented on Fig. 1 of the drawings.

In practice the rods E are loosened or tightened at will by the turn-buckle arranged between them, and in tightening, the braces G are pressed down firmly against the upper surface of the longitudinal brace D, and spring it downward. This brace then serves as a retraction-spring and keeps the saw taut and in line.

Having described my invention, what I claim is—

In a bucksaw, the combination, with the end bar and handle-bar, of the longitudinal bowed brace having the upward curve, the oblique braces G, having their ends forked, and one end of each brace secured to the upper side of the longitudinally-bowed brace and the opposite end secured to the upper inner side of the end bar and handle-bar, respectively, as set forth.

In testimony whereof I affix my signature in presence of two witnesses.

WILLIAM HANKIN, SR.
